UNITED STATES PATENT OFFICE

135,701

DESIGN FOR A SLIP OR SIMILAR ARTICLE

Frances Hawkes, Des Moines, Iowa, assignor to Rollins Hosiery Mills, Inc., Des Moines, Iowa,
a corporation of Delaware

Application February 26, 1943, Serial No. 109,630

Term of patent 14 years

To all whom it may concern:

Be it known that I, Frances Hawkes, a citizen of the United States of America, residing at 3333 Grand Street, Des Moines, in the county of Polk, State of Iowa, have invented a new, original, and ornamental Design for a Slip or Similar Article, of which the following is a specification, reference being had to the accompanying drawing, forming part thereof, and in which:

Fig. 1 is a front view of a slip showing my design;

Fig. 2 is an enlarged fragmentary view of the slip shown in Fig. 1 illustrating the embroidered trim in detail; and,

Fig. 3 is a rear view, on reduced scale, of the slip shown in Fig. 1.

The characteristic feature of my design resides in the combination on the slip disclosed of the specific embroidery, as shown.

I claim:

The ornamental design for a slip or similar article, as shown and described.

FRANCES HAWKES.
